DRESSER OR THE LIKE

Huey T. Keller, 1609 Davidson Road,
High Point, N.C. 27260

Continuation-in-part of design application Ser. No. 24,385,
Aug. 10, 1970. This application Feb. 16, 1973, Ser.
No. 333,131

Term of patent 14 years

Int. Cl. D6—04

U.S. Cl. D6—154

75 4

FIG. 1 is a front elevational view of the dresser or the like showing my new design, the rear of the same being substantially plain and unornamented;

FIG. 2 is a section taken through lines 2—2 of FIG. 1;

FIG. 3 is a section taken through lines 3—3 of FIG. 1;

FIG. 4 is an end elevational view of the design, the opposite end being substantially a mirror image of that shown; and

FIG. 5 is a top plan view of such design.

I claim:

The ornamental design for a dresser or the like, as shown.
